PREPARATION OF ISOPROPYL BENZENE HYDROCARBONS

Gordon E. Langlois, El Cerrito, Calif., assignor to California Research Corporation, San Francisco, Calif., a corporation of Delaware

No Drawing. Application June 25, 1953,
Serial No. 364,219

5 Claims. (Cl. 260—671)

This invention relates to an improved process for the preparation of isopropyl benzene hydrocarbons. More particularly, the invention has to do with the preparation of cumene, the cymenes, dimethyl isopropyl benzenes, and polyisopropyl benzenes by the alkylation with propene of benzene, toluene, and xylene, in the presence of a phosphoric acid catalyst of a particular concentration and under controlled alkylation conditions, whereby improved utilization of the benzene hydrocarbons is obtained.

The aforesaid isopropyl benzene hydrocarbons, especially cumene, are useful as additives in, or as constituents of, aviation gasoline. In commercial practice, the alkylation is effected by contacting the appropriate benzene hydrocarbon with a propene-containing stream, such as a petroleum refinery stream (C₃ cut) obtained as a by-product of certain refinery operations, such as cracking, under alkylation conditions, falling within wide ranges and in the presence of an alkylation catalyst, such as sulfuric acid or of the solid phosphoric acid type falling within wide concentration ranges. In commercial practice the propene employed, usually obtained from petroleum refinery operations, such as cracking, normally has substantial quantities of the butene homologs associated with it. The presence of these are not objectionable however, since they give rise to butyl aromatic hydrocarbons, which are also useful. For example, butyl benzene is a rich-rating additive in its own right, having engine performance properties comparable with those of cumene.

Broadly, the invention is predicated on the discovery that the preparation of the aforementioned isopropyl benzene hydrocarbons is made substantially more efficient by a process which comprises contacting the appropriate benzene hydrocarbon in the presence of phosphoric acid catalyst falling within a narrow concentration range, based on orthophosphoric acid, and at an alkylation temperature also falling within a narrow range, as a result of which substantially improved utilization of the benzene hydrocarbon occurs. More particularly, alkylation temperatures fall between about 300° F. and 400° F., while the concentration of the phosphoric acid catalyst employed during reaction resides within about the range of 96% to 104%, based on orthophosphoric acid, and preferably between about 99% and 101%, based on orthophosphoric acid. This concentration is controlled by the amount of water in the feed, including propene and benzene hydrocarbon, during reaction. As will occur to those skilled in the art, the amount of water required in the feed to maintain a given acid concentration will depend on the temperature, pressure, composition of the feed, and fraction of the reaction mix vaporized. The amount of water added is such that the partial pressure of water in the vapor phase is equal to the vapor pressure of water of the particular con-

centration of acid desired at the temperature under consideration. Thus, at an average temperature of 350° F. and at an average pressure of 250 p. s. i. g. with a total reactor feed consisting of 8.0 weight per cent propene, 17.0 weight per cent propane and 75.0 weight per cent benzene hydrocarbon, about 0.29 per cent of water, by weight, of the total feed, including propene and benzene hydrocarbon, charged to the reactor, will result in an acid concentration of 96%, with about 0.07% water and about 0.013% water, resulting, respectively, in acid concentrations of 100% and 104%.

The type of catalyst contemplated by the invention is not critical. In addition to the bulk liquid phosphoric acid catalyst, suitable catalyst material is the solid phosphoric acid type prepared by impregnating a diatomaceous earth, e. g., kieselguhr, followed by calcining, as described, for example, in U. S. Patent No. 2,375,724; the acid-film type of phosphoric acid, wherein the acid is disposed as a thin film on an inert, non-porous support, such as quartz, as described, for example, in U. S. Patents Nos. 2,135,793 and 2,186,021; and the metal pyrophosphates, e. g., copper pyrophosphate, as described in U. S. Patents Nos. 2,310,161 and 2,414,206. Preferred catalysts are the bulk liquid phosphoric acid, and the acid-film, the latter having a film of acid disposed on crushed quartz particles of 28-35 mesh.

In further description of the invention, tabulated below in Table I are operating conditions under which a number of experiments were performed, together with the data obtained therefrom, in the preparation of cumene. In carrying out the experiments, a fresh petroleum refinery C₃ stream was caustic treated to remove sulfur compounds, and water washed to remove any nitrogen bases, and then dried. The benzene recycle, obtained from a topping still, employed in a later step of the process, was also dried, combined with the C₃ cut and this feed preheated, after which a sufficient amount of water was added to maintain the desired acid concentration. The preheated feed together with the water was pumped into the top of a reactor comprising a 2-inch by 10-foot tube packed with catalyst, the feed passing downflow therethrough. The tube was filled approximately one-half full, the total catalyst volume being about 3,000 cc. The catalyst was phosphoric acid on 28 to 35 mesh crushed quartz. Reactor temperature was controlled by circulating oil in the jacket of the reactor. The temperature in the reactor rose as a result of the exothermic heat of reaction, the temperature rise averaging about 50° F. The temperature was measured at five points along a thermowell placed in the center of the reactor, and the average temperature was the arithmetic mean of these five points. Reaction mix from the reactor flowed to a stabilizer which was a 2-inch by 6-foot packed column operated at 250 p. s. i. g. The overhead tail gas was metered, sampled, and discarded. Stabilizer bottoms were pumped to a topping still, a 3-inch by 6-foot packed column operated at atmospheric pressure. From the topping still recycle benzene was taken overhead and passed into calibrated feed vessels from which it was pumped back to the reactor. Fresh makeup benzene was added to the recycle feed vessels as necessary to maintain the inventory approximately constant. Total benzene inventory within the plant, including the feed vessels, reactor, and stills was such that it made a complete cycle through the plant every two to three hours. The topping still bottoms were withdrawn and fractionated batchwise to separate the isopropyl benzene hydrocarbon.

³ H₃PO₄ on 28-35 mesh crushed quartz.

Inspection of Table I reveals that in order to obtain the highest benzene utilization the simultaneous observation of the two conditions of temperature and acid concentration must be made. Thus, in run number 14-1, a benzene utilization of 93.8% was obtained. The acid concentration in the run was 106%, that is, beyond the tolerable maximum of 104%, although the temperature of 393 was well within the range of 300-400° F. Lowering the temperature to about 300° F., while maintaining the acid concentration of 106%, run 14-6, did not improve benzene utilization. It will be noted, however, that good benzene utilization was had in run number 14-16. Here the temperature was 354° F., and the acid concentration 100%, the temperature and acid concentration falling within suitable ranges. However, increasing the temperature decreases benzene utilization as shown in run number 14-20 even though a low acid concentration is maintained.

Tabulated below are operating conditions and results of runs in the preparation of cymene.

TABLE II
Combined effect of temperature and acid concentration on toluene utilization

Run Number	1	2
Catalyst	(¹)	(¹)
Temperature, ° F.	400	500
Pressure, p. s. i. g.	200	200
Total Feed Rates, Liq. v./v./hr.	2.0	2.0
Feed Composition, Wt. Percent:		
Propene	7.6	6.4

Toluene-Propene Mol Ratio	5.6	6.6
Composition of Alkylate, Wt. Percent:		
Cymene	95.5	90.2
Higher boiling material	4.5	9.8
Toluene Utilization	96.5	92.3
Acid Concentration, percent	101	106

¹ Solid phosphoric acid.

Toluene was alkylated with propene, to produce cymene by the procedure utilized in obtaining the data of Table I, except that the toluene was not recycled under the above conditions.

⁵ It will be noted that substantially greater toluene utilization (96.5%) occurs with low acid concentration and low temperature, run 1, as compared with that of run 2, (92.3%), wherein high acid concentration and high temperature were employed.

Obviously many modifications and variations of the invention as hereinbefore set forth may be made without departing from the spirit and scope thereof, and therefore only such limitations should be imposed as are indicated in the appended claims.

I claim:

1. In the process of preparing an isopropyl aromatic hydrocarbon by alkylating a benzene hydrocarbon having a molecular weight not exceeding that of xylene with propene, the improvement of effecting greater utilization of the benzene hydrocarbon, which comprises reacting the benzene hydrocarbon with propene at a pressure in the range of from about 200 to 1800 p. s. i. g. and at a temperature of at least about 300° F. but not exceeding about 400° F. in the presence of a liquid non-adsorbed phosphoric acid catalyst of a concentration of at least about 96% but not exceeding 104%, based on orthophosphoric acid.

2. Improvement substantially as described in claim 1, wherein the phosphoric acid catalyst is disposed as a film on crushed quartz of 28 to 35 mesh particles.

3. Improvement substantially as described in claim 1, wherein the acid concentration is about 99% to 101%, based on orthophosphoric acid.

4. Improvement substantially as described in claim 1, wherein the benzene hydrocarbon reacting with the propene is present in a mol ratio of about 3 to about 5 mole of benzene hydrocarbon per mol of propene.

5. Improvement substantially as described in claim 1, wherein alkylation pressures range from about 200 to 500 p. s. i. g.
